tober 13, 1943, Serial No. 506,023

3 Claims. (Cl. 123—179)

1

This invention relates to an inertia starting system for internal combustion engines, and particularly the engines of vehicles such as airplanes and the like.

This application is a division of S. N. 459,566 entitled "Engine starting system," filed September 24, 1942, patented April 11, 1944, No. 2,346,303.

Heretofore it has been the usual practice to include in this type of starter a plurality of components including an electric motor, a flywheel, reduction gearing, extensible jaw clutch member, and a torque limiting clutch all contained in a single housing having a flange attachment with the crank case of the engine. This unitary arrangement has certain obvious advantages, but it also possesses inherent disadvantages rendering it unsuitable for use on some engines. In some installations space limitations prohibit the addition of a large starter unit on the engine, due to proximity of a bulkhead or fire wall, or to the presence of a multiplicity of accessories on the rear of the engine. Further, even though there is sufficient space it is still desirable to avoid subjecting the electric starting motor to the engine vibration, notwithstanding the tendency in the prior art to disregard this consideration.

It is therefore the object of the present invention to separate the components of the starting system so that a relatively smaller unit may be mounted directly on the engine and so that the electric starting motor may be mounted on the airplane or vehicle where the vibration is less severe than on the engine.

A particular object is to provide an improved engine starting system having only those components driven by the inertia flywheel mounted directly on the engine, the flywheel energizing means being separately mounted on the vehicle.

A further object is to provide an engine starting system having an inertia starter mounted on the engine, having an electric motor for energizing the inertia member of said starter mounted in the engine compartment and connected with the starter by a flexible shaft, and having a hand crank receiving unit accessible exteriorly of said compartment and connected with said motor by a flexible shaft to drive said inertia member.

Additional and more specific objects and advantages will be apparent to those skilled in the art as the description proceeds in connection with the accompanying drawings showing by way of example a preferred embodiment of the invention.

In the drawings:

Figure 1 is a schematic representation of the starting system of the present invention, showing

2

the functional relation of the various units thereof;

Figure 2 is a perspective view of the starting system showing its physical disposition in an application to an airplane or like vehicle;

Figure 3 is a top plan view of a portion of the engine compartment shown in Figure 2;

Figure 4 is a cross sectional view taken on the line 4—4 of Figure 3;

10 Figure 5 is a wiring diagram showing the energizing circuits for the starting motor and the jaw meshing solenoid;

15 Figure 6 is a view in perspective of the gear box, or flexible shaft adapter, with its cover removed to show the connection and gear drive between the hand crank flexible drive and the starter motor shaft.

20 Referring first to Figures 1 to 4, it will be seen that the present starting system comprises a plurality of separate components connected by flexible shafts. Mounted upon the internal combustion engine 9 to be started is the inertia starting unit 10, the inertia member thereof being energized by means of the flexible shaft 11 from an electric motor 12. The motor 12 is preferably mounted on some part of the airplane adjacent the engine, such as the bulkhead or fire wall 13, for reasons which will later be discussed. A hand crank receiving unit 14 is mounted on the airplane close to the engine compartment in a position for convenient access to the portable hand crank mechanism 15. The hand crank receiving unit is connected with the motor 12 by the flexible shaft 16. The numeral 17 indicates the skin of the fuselage or nacelle of the airplane.

25 30 35 The operating relation of the units forming the component parts of the starting system is illustrated schematically in Figure 1 without reference to a particular kind of craft or vehicle, while Figures 2 to 4 illustrate a preferred embodiment of the physical disposition of the units and associated control elements in an airplane. The electrical circuits for the starting motor and jaw meshing solenoid are disclosed in the wiring diagram of Figure 5. The individual units will now be described before proceeding with further discussion of the system as a whole.

Inertia starter unit

40 45 50 The starter unit 10 is provided with a supporting flange 19 adapted to be bolted to the crankcase of the engine to be started so as to bring an extensible jaw clutch member 20 closely adjacent a similar jaw member on the engine. The member 20 is splined for rotation with and longitudinal

movement in a rotatable member geared through an overload release clutch 25 to a flywheel 33. The flywheel is accelerated to a high speed by means of a bevel gear 30 on the flexible drive shaft 11, this shaft being attached to an extension 40 on the starter unit by means of a threaded union member 41 or the like.

The jaw clutch member 20 normally reposes in the retracted position shown in full lines in Figure 1, and to crank the engine this member must be extended to engage the clutch member on the engine. The mechanism for retracting and extending the jaw clutch member 20 includes the push rod 44 which is arranged to be extended by the rocker arm 45 as shown schematically in the wiring diagram in Figure 5. Electrical operation is effected through a bell crank lever 49 actuated by a plunger 50 in a solenoid 51, the circuit to which is established through the conductor cable 102 leading to a switch 104 in the pilot's compartment. Manual operation of the rocker arm 45 is effected by means of the pull cable 47, the disposition of which will be hereinafter referred to in connection with the hand cranking mechanism and in connection with the discussion of the system as a whole.

The starter unit 10 is shown in greater detail in the parent application above referred to, and the jaw meshing mechanism is disclosed in detail and claimed in my copending application Serial No. 439,751, filed April 20, 1942 for Jaw meshing mechanism for electric starters, patented November 9, 1943, No. 2,334,003.

Electric motor

The motor unit 12 is provided with a base 60 for attachment to any suitable support adjacent the engine and the starter unit 10, such as, for instance, the bulkhead 13. To allow for the most convenient disposition of the motor in any particular installation the base 60 is secured to a band 61 encircling the motor housing or frame and adjustable throughout a range of 360 degrees therearound. An axial extension 62 on the end of the motor housing secures one end of the housing of the flexible shaft 11, maintaining the flexible shaft in rotative engagement with the end of the motor shaft.

The other end of the motor is adapted to receive another flexible shaft drive for manual operation by means of hand cranking equipment to be presently described. For this purpose a housing extension 63 having a socket 200 adapted to secure the flexible shaft 16 in driving engagement with an overrunning clutch 64 (Figures 4 and 6) which is preferably of the centrifugal type disclosed and claimed in my copending application Serial No. 434,235, filed March 11, 1942 for Centrifugal clutch patented October 26, 1943, No. 2,333,007, see Figure 1. A spiral bevel gear 201 and a spiral bevel pinion 202 complete the power connection with the commutator end of the motor shaft 11. The clutch member comprises a pair of centrifugal dogs 203 driven by the shaft 16 and adapted to engage internal projections in an encircling clutch member 64 connected with one of said gears when said shaft is driven in the proper direction. If the rotation of said shaft is reversed the dogs will cam themselves over the internal projections without causing it to rotate, and similarly when the motor is energized to furnish the power source the projections ride over the dogs without turning the hand crank shaft 16. This construction renders it impossible to crank the inertia flywheel in the wrong

direction and prevents the driving of the hand crank shaft by the motor.

The motor 12 is equipped with brush lifting mechanism operable by a flexible control wire 81 from the pilot's compartment or other station. This mechanism is disclosed and claimed in the parent application and forms no part of the instant application.

Hand crank mechanism

In lieu of energizing the inertia starting member, or flywheel 33, by the electric motor means 12, the hand crank mechanism indicated generally by the numeral 15 may be used. The hand crank mechanism comprises essentially a detachable crank handle 90, a detachable gear box 91, a crank and gear box receiver 14, and the flexible shaft 16. The gear ratio of the gear box 91 is preferably approximately 80:1, causing the shaft 16 to make about eighty revolutions for every revolution of the crank. This turning effort is transmitted through the overrunning clutch 64 to the motor 12 which in turn drives the flywheel 33 through the flexible shaft 11. It is intended that the crank 90 and gear box 91 be detachable for stowing in the airplane when not required for use, this equipment being primarily for emergency use only.

The hand crank receiver 14 is preferably welded to a rigid part of the vehicle frame or fuselage 92 by means of struts 93 or the like and is located to present the most convenient access for hand cranking consistent with relatively short flexible shaft connections and the limitations to the curvature thereof. As illustrated in the present embodiment the crank 90 extends on the outside of the fuselage 17 with the shaft 16 on the inside. The crank may obviously be located within the vehicle if the construction and arrangement are suitable. The gear box 91 is supported by an integral tubular shank 94 adapted to fit in a tubular sleeve forming the body of the receiver 14. A squared hole in a stub shaft within the said shank 94 is adapted to receive a squared end on the flexible shaft 16, this association of parts being maintained by cooperating pins and bayonet slots on the shank 94 and receiver 14, respectively.

The hand crank mechanism per se constitutes the subject matter of my separate application, Serial No. 431,850, filed February 21, 1942, for Hand crank mechanism, patented June 29, 1943, No. 2,323,135 and assigned to the assignee of the present invention.

Controls

The controls for the previously described jaw meshing and brush lifting mechanisms are of two types, electrical and mechanical, and are disposed in the pilot's compartment and adjacent the hand crank receiver in the proximity of the engine compartment, but it is to be understood that this arrangement while at present preferred is illustrative only.

65 The pull cable 47 for effecting manual operation of the jaw meshing mechanism terminates in a loop or handle 95 accessible through the outer wall of the engine compartment adjacent the hand crank receiver 14. When the cable is pulled the rocker arm 45 depresses the push rod 44 to extend the jaw clutch member 20. When the pull cable is released the push rod is returned by spring means carrying the member 20 back to retracted position.

75 The numeral 100 indicates a battery or other

source of electrical supply for the starting system. The representation of the battery in Figure 2 is merely for the purpose of completing certain circuit connections, and is not intended to illustrate a preferred physical disposition of the electrical power source. Referring now to Figure 5, one side of the battery circuit is grounded at 101 and the other side divides into two conductors 102 and 103. The conductor 102 is connected with switches 104 and 105 in the pilot's compartment, the switch 104 controlling a circuit 106 to the jaw meshing solenoid 51, and the switch 105 controlling a circuit 107 to a relay solenoid 108 in a power relay 109 in the circuit 103, 110 of the starting motor 12. Plug connectors 111 and 112 are built into the motor and inertia starting units, respectively, the return sides of the circuits being completed to ground as shown.

A button 115 in the pilot's compartment operates the flexible wire control 81 for the brush lift- 20 ing mechanism on the motor.

Operation

In the present arrangement it will be seen that only the inertia starter unit 10 is subjected directly to engine vibration, the motor unit 12 being mounted on the bulkhead 13 or other structural part where the vibration is much less severe. Also, by thus separating the motor and starter units the motor may be disposed where it will least interfere with the numerous accessories associated with airplane power plants and the like, and at the same time reduce the clearance which would otherwise be required between the rear end of the engine crankshaft and the bulkhead 13.

Regardless of whether the inertia starter is energized by the hand crank or the electric motor the flexible shaft 11 transmits the necessary torque to the starting unit 10 to accelerate the flywheel therein. The second flexible shaft 16 enables the hand crank receiver 14 to be located in an accessible position without the necessity for a straight line connection with the motor. In Figures 2, 3 and 4 the starting system of the present invention is applied to an airplane of the type having the engine behind the cockpit, or pilot's compartment, but it is to be understood that this arrangement is shown for purposes of illustration only, since the present starting system may also be used on engines forward or laterally of the cockpit. It is also to be understood that the flexible shaft connections with the various units may be varied to best suit the particular installation. For instance, the radial connection of the flexible shaft 16 through the housing extension 63 may be readily changed to an axial connection by merely substituting interchangeable parts. Likewise, the power cable 110 may be end connected instead of side connected. The flexible shaft and electrical connections are thereby adaptable to varied types of installations in addition to the specific embodiment illustrated.

To energize the inertia starter electrically the control button 115 is first pressed in, causing the motor brushes to be pressed against the commutator under spring action. Then, upon closing the switch 105 the motor 12 will accelerate the inertia flywheel 33 to its proper operating speed. Closing of the switch 104 will energize the jaw meshing solenoid 51 to extend the jaw clutch member 20 to crank the engine. As long as the starter is delivering torque to the engine the friction between the jaw clutch member on the starter and the jaw clutch member on the engine will hold the two members in engagement but, when the engine 75

fires, the member 20 is automatically released for return to its retracted position. If the starter is purely of the inertia type the motor switch 105 is opened when the jaw meshing switch 105 is closed, but if the starter is of the combination type, utilizing both inertia and direct cranking, the motor switch 105 is not opened until it is desired to terminate the cranking operation.

When the engine is to be started by hand cranking, the motor brushes are first lifted by pulling out the button 115. The portable hand crank and gear box are inserted in the receiver 14 and the crank is turned in the proper direction to spin the flywheel 33, it being remembered that the over running clutch 64 prevents cranking the flywheel in the wrong direction. When the desired flywheel speed is attained the engine may be cranked by pulling on the jaw meshing cable 47 to extend the jaw clutch member 20 into engagement with the engine. Once the jaw clutch members are properly engaged the cable 47 may be released and the engagement will be maintained by contact friction between the members until torque is no longer being delivered to the engine. After the starting operation the hand crank and gear box may be removed from the receiver 14 and stowed in the airplane.

While the present starting system has especial utility in aircraft of both the heavier-than-air and lighter-than-air types, it is also applicable to land and marine vehicles and to stationary engines as well. It is obvious that the switches 104, 105, and the control button 115, herein illustrated as being mounted on a control panel 120 in the pilot's compartment, may be located wherever the electrical and mechanical controls may be manipulated and that the hand crank receiver 14 may be located in the same compartment with said controls, or in another compartment, provided the distance from the motor 12 does not exceed the limitations of available flexible shafting.

Various other changes may be made in the arrangement, and certain parts of the system may be used without other parts. All such modifications and sub-combinations are included in the invention, it being understood that the same is to be limited only by the scope of the appended claims.

I claim:

1. A starting system for an internal combustion engine in a vehicle comprising an inertia starter unit mounted on said engine, an electric motor mounted on said vehicle adjacent said starter unit so as to be subject to less vibration than said starter unit, a flexible shaft drive connecting one end of said motor with said starter unit, an overrunning clutch incorporated in the other end of said motor and having its driven element connected with the motor shaft, a hand crank receiving unit mounted on said vehicle in an accessible position, and a flexible shaft drive connecting said crank receiving unit with the driving element of said clutch.

2. A starting system for an internal combustion engine in a vehicle comprising an inertia starter unit mounted on said engine, an electric motor mounted on said vehicle adjacent said starter unit so as to be subject to less vibration than said starter unit, a flexible shaft drive connecting one end of said motor with said starter unit, an overrunning clutch incorporated in the other end of said motor and having its driven element connected with the motor shaft, a hand crank receiving unit mounted on said vehicle in an accessible position, and a flexible shaft drive connecting said

crank receiving unit through gearing with the shaft of said motor.

3. A starting system for an internal combustion engine in a vehicle comprising an inertia starter unit mounted on said engine, an electric motor mounted on said vehicle adjacent said starter unit so as to be subject to less vibration than said starter unit, a flexible shaft drive connecting one end of said motor with said starter unit, an overrunning clutch incorporated in the other end of said motor and having its driven element connected with the motor shaft, a hand crank receiving unit mounted on said vehicle in an accessible position and a flexible shaft drive connecting said crank receiving unit with the driving element of said clutch and through said clutch and gearing

connected to the driven element of said clutch to the shaft of said motor.
